United States Patent Office

Des. 232,711
Patented Sept. 10, 1974

232,711

AIRPLANE

Mark E. Kirchner, Mercer Island, and Philip C. Whitener,
Seattle, Wash., assignors to The Boeing Company,
Seattle, Wash.

Filed Dec. 26, 1972, Ser. No. 318,070

Term of patent 14 years

Int. Cl. D12—07

U.S. Cl. D12—76

FIG. 1 is a top plan view of an airplane depicting our new design;

FIG. 2 is a front elevational view;

FIG. 3 is a bottom plan view; and

FIG. 4 is a side elevational view.

The broken line disclosure of landing gear is for illustrative purposes only.

What is claimed is:

The ornamental design for an airplane, as shown and described.
